UNITED STATES PATENT OFFICE.

EMIL A. HOEFER, OF FREEPORT, ILLINOIS, ASSIGNOR TO HOEFER
MANUFACTURING COMPANY, OF FREEPORT, ILLINOIS.

WIRE-KNOTTING MACHINE.

No. 854,354.

Specification of Letters Patent.

Patented May 21, 1907.

Application filed November 27, 1905. Serial No. 289,356.

To all whom it may concern:

Be it known that I, EMIL A. HOEFER, a citizen of the United States of America, residing at Freeport, in the county of Stephenson and State of Illinois, have invented certain new and useful Improvements in Machines for Knotting Wire, of which the following is a specification.

This invention relates specifically to a machine for knotting the free ends of coiled springs about their adjacent coils; and it consists of the new and useful features of construction and combinations of parts, embodied in the herein-described machine, which are hereinafter fully described and specifically pointed out in the claims appended hereto.

Referring to the accompanying drawings, which form a part of this specification, Figure 1 is a side elevation of a machine, embodying my invention. Fig. 2 is an end elevation of the same. Fig. 3 is a section, at the dotted line 3—3, in Fig. 1, of parts there shown, with other parts in elevation. Fig. 3^a is a detail view of a part shown in Fig. 3. Fig. 4 is a top plan view of the machine. Fig. 5 is a section, at the dotted line 5—5, in Fig. 1, of parts there shown, with other parts in elevation. Figs. 6 and 7 are horizontal sectional details of parts of the machine serving to illustrate its mode of operation. Fig. 8 is a top plan view of the lower clamping-jaw of the machine. Fig. 9 is a side elevation of the same. Fig. 10 is a view showing one end of a coiled spring knotted to its adjacent coil.

Like letters of reference indicate corresponding parts throughout the several views.

A is the main frame of the machine and is provided with shaft-bearings A¹ A² A³ A⁴.

B is a shaft mounted in the bearings A¹ A² in the frame A.

B¹ is a cam for operating a part to be described hereinafter and is fast to the shaft B.

B² is a cam-plate eccentrically mounted fast on the shaft B and having an oval cam-groove B³ formed in the outer face thereof. The part B² will be hereinafter referred to, for brevity, as the platen-actuating cam.

C is a clamping-jaw and platen support, which is preferably in the form of a bell-crank pivotally mounted, by the free end of one arm C¹, to a bearing C² on the frame A, and having the free end of its remaining arm

C³ provided with a transversely-mounted roller or other stud C⁴ projecting therefrom into engagement with the groove B³ in the platen-actuating cam B².

B⁴ is a spring-supporting platen and is preferably integral with its support C.

D is a lower clamping-jaw having a curved groove D¹ formed in the upper face thereof and mounted fast on the horizontal arm C³ of the support C.

D² D³ are pins, seated in vertical sockets in the jaw D and serving as gages for maintaining the two coils of wire, as a a¹, being knotted together, at predetermined distances from each other.

E is an upper clamping-jaw, pivoted by its rear end on a bearing E¹ on the arm C³ of the support C and adapted to coöperate with the jaw D to firmly grip two coils of wire a a¹ while the former is being knotted about the latter.

F is a circular stud, rotatably and eccentrically mounted, by means of a portion F¹ thereof of diminished diameter, in a corresponding bearing in the frame A and serving to maintain the latter firmly closed upon the coils of wire to be knotted together. By turning the eccentrically mounted stud F in its bearing F¹, it may be adapted to contact and maintain the jaw E closed upon wires of any desired diameter, within the limits of the machine.

G is a sector-gear mounted fast on the shaft B.

H is a shaft mounted in the bearings A³ A⁴ in the frame A.

H¹ is a collar mounted fast on the shaft H and having a detent-notch H² in the periphery thereof.

H³ is a detent-lever pivotally mounted, between its ends, on a bearing H⁴ and provided with a detent H⁵, adapted to engage the notch H² in the collar H¹ and thereby prevent the rotation of the shaft H at predetermined times, and having a lug H⁶ thereon projecting downwardly into engagement with the periphery of the cam B¹ on the shaft B.

I, Fig. 5, is a gear-wheel, mounted fast on the shaft H and adapted to mesh with and be driven by the toothed portion of the sector-gear G.

J is a knotted-pinion, having a conical recess J¹, Figs. 6 and 7, in its outer end, a

radial recess J^2 , in its inner end, and a radial slot J^3 therein connecting such conical and radial recesses J^1 J^2 , and rotatably mounted in bearings J^4 J^5 in the frame A.

5 K, Fig. 6, is a gage-stop for the free end of a coil a , of a spring P, to be knotted about a coil a^1 thereof.

L is a driving-pulley, having a plurality of transverse sockets L^1 in the inner end of the hub L^2 thereof and mounted loose on the shaft B.

M, Fig. 4, is a clutch-body mounted fast on the shaft B.

15 M^1 is a longitudinally-slidable spring-actuated detent, housed in the clutch-body M, adapted to engage with and be disengaged from the sockets L^1 , in the hub L^2 of the pulley L, and provided with a cam-head M^2 , Fig. 1, fast to the outer end of such detent.

20 N is a rock-shaft mounted in bearings in the frame A.

N^1 is an arm fast, by one end, to the outer end of the rock-shaft N and having its free-end portion engaging the cam-head M^2 of the detent M^1 , through the action of the spring N^2 , and thereby normally maintaining such detent M^1 out of engagement with the loose pulley L.

25 N^3 is a foot-lever pivoted, by one end and at N^4 , to the frame A, and having its free end pivotally connected, by means of the rod N^5 , to the middle portion of the arm N^1 .

30 In Fig. 1 the detent M^1 is held out of engagement with the loose pulley L by the action of the spring N^2 upon the arm N^1 .

35 O O^1 , Fig. 2, are pins rigid with the parts C and E respectively.

40 O^2 is a tension spring maintaining the upper jaw E out of engagement with the lower jaw D and in contact with the eccentrically mounted stud F.

45 The detent H^5 , Fig. 3, is maintained in engagement with the notch H^2 , in the collar H^1 on the shaft H, and the latter, with its gear-wheel I is thereby prevented from rotating while the platen B^4 is traveling from the position shown in Fig. 6 to that shown in Fig. 7. Simultaneously with the completion of the inward movement of the platen, the lug H^6 on 50 the lever H^3 will have passed onto the cut-away portion of the cam B^1 , and the detent H^5 will have disengaged from the collar H^1 , thereby leaving its shaft H free to be rotated to turn the gear-wheel I to drive the knotter-pinion J. Simultaneously with the completion of the knotting operation of the pinion J, the lug H^6 will have passed from the cutaway to the wider portion of the cam B^1 , thereby again causing the detent H^5 to lock 55 the shaft H while the platen is traveling from the position shown in Fig. 7 back to that shown in Fig. 6.

60 Supposing the pulley L to be running loosely on the shaft B, and the two lower coils 65 of a spring P to be resting on the platen B^4

and lower jaw D, in the positions shown in Fig. 6, the operation of the machine, if the foot-lever N^3 be depressed until the detent M^1 engages one of the sockets L^1 in the hub L^2 , will be as follows: The shaft B, Fig. 2, 70 will be rotated and turn the part b , on the platen-actuating cam B^2 , from contact with the stud-roller C^4 to the position it is shown as occupying in Fig. 2, thereby advancing the platen and spring inward, from the position shown in Fig. 6 to that shown in Fig. 7, with the result that the free-end portion a^2 of the spring will have been bent at right angles to its coils a a^1 , by the action of the bottom of the radial recess J^2 in the knotter-pinion J. 80 Immediately thereafter the teeth of the sector-pinion G will engage and turn the gear-wheel I one revolution, and the latter will turn the knotter-pinion J two revolutions and thereby wrap and knot the free-end portion a^2 of the coil a about the coil a^1 , producing the finished structure shown in Fig. 10. During the knotting operation just described, the part b , on the cam B^2 , will have traveled from the position shown in Fig. 2, to that indicated by b^2 , and the platen B^4 will have remained motionless. The cam B^2 will then continue to rotate until the point b thereon is again in contact with the roller-stud C^4 , the platen will then assume the position shown 95 in Fig. 6 and the clamping-jaws of the machine will be opened to release the spring.

Having fully described my invention, what I claim as new and desire to secure by Letters Patent, is—

1. In a machine of the class described, in combination, a supporting-frame, a shaft mounted therein, a cam-plate eccentrically mounted fast on the shaft and having an oval cam-groove in the outer face thereof, a clamping-jaw and platen support, with its platen, preferably in the form of a bell-crank and pivotally mounted, by the free end of one arm, to a bearing on the frame, and having the free end of its remaining arm provided with a transversely-mounted stud projecting therefrom into engagement with the oval groove in the cam-plate, a lower clamping-jaw mounted fast on the platen-support, and an upper clamping-jaw, pivoted on the platen-support and adapted to coöperate with the lower jaw, substantially as described.

2. In a machine of the class described, in combination, a supporting-frame, a shaft mounted therein, a cam-plate eccentrically mounted fast on the shaft and having an oval cam-groove in the outer face thereof, a clamping-jaw and platen support, with its platen, preferably in the form of a bell-crank and pivotally mounted, by the free end of one arm, to a bearing on the frame, and having the free end of its remaining arm provided with a transversely-mounted stud projecting therefrom into engagement with the oval groove in the cam-plate, a lower clamping-

jaw mounted fast on the platen-support, an upper clamping-jaw, pivoted on the platen-support and adapted to coöperate with the lower jaw, a knotter-pinion, having a conical recess in its outer end, a radial recess in its inner end, a radial slot therein, connecting the conical and radial recesses, and rotatably mounted in bearings in the frame, a sector-gear mounted fast on the cam-plate shaft, a gear-wheel located between and meshing with both the knotter-pinion and sector-gear, and a shaft carrying said sector-gear, substantially as described.

3. In a machine of the class described, in combination, a supporting-frame, a shaft mounted therein, a cam-plate eccentrically mounted fast on the shaft and having an oval cam-groove in the outer face thereof, a clamping-jaw and platen support, with its platen, preferably in the form of a bell-crank and pivotally mounted, by the free end of one arm, to a bearing on the frame, and having the free end of its remaining arm provided with a transversely-mounted stud projecting therefrom into engagement with the oval groove in the cam-plate, a lower clamping-jaw mounted fast on the platen-support, an upper clamping-jaw, pivoted on the platen-support and adapted to coöperate with the lower jaw, a rotatably and eccentrically mounted stud, adapted to contact and close the upper clamping-jaw upon wire-spring coils, of various diameters, supported

by the lower clamping-jaw, substantially as described.

4. In a machine of the class described, in combination, a supporting-frame, the shafts B H mounted therein, a cam-plate B² fast on the shaft B and having an oval cam-groove B³ therein, a clamping-jaw and platen support C pivotally mounted, by the free end of one arm C¹, to a bearing on the frame, and having the free end of its remaining arm C³ provided with a transversely-mounted roller-stud C⁴ projecting into engagement with the groove B³ in the cam-plate B², a lower clamping-jaw D fast on the platen-support C, an upper clamping-jaw E, pivoted on the platen-support and adapted to coöperate with the lower clamping-jaw D, a knotter-pinion J, having a conical recess J¹ in its outer end, a radial recess J² in its inner end, a radial slot J³ therein, connecting the conical and radial recesses, and rotatably mounted in bearings in the frame, a sector-gear G fast on the shaft B, a gear-wheel I located between and meshing with the knotter-pinion J and sector-gear G, and a shaft carrying said sector-gear G, substantially as described.

In testimony whereof I have signed my name to this specification in the presence of two subscribing witnesses.
